UNITED STATES PATENT OFFICE.

JOHN S. KERFOOT, OF OKLAHOMA, OKLAHOMA.

SAFETY-NET FOR ELEVATOR-SHAFTS.

No. 896,213.

Specification of Letters Patent.

Patented Aug. 18, 1908.

Application filed May 28, 1907. Serial No. 376,095.

To all whom it may concern:

Be it known that I, JOHN S. KERFOOT, a citizen of the United States, residing at Oklahoma city, in the county of Oklahoma, Oklahoma, have invented a new and useful Safety-Net for Elevator-Shafts, of which the following is a specification.

The invention relates to a safety net for elevator shafts.

10 The object of the present invention is to provide a simple, inexpensive and efficient safety net, adapted to be placed in an elevator shaft at the bottom thereof, without interfering with the operation of the elevator, 15 and capable of cushioning the fall of a person down the elevator shaft to prevent a serious injury resulting from an accident of that character.

With these and other objects in view, the 20 invention consists in the construction and novel combination of parts hereinafter fully described, illustrated in the accompanying drawing, and pointed out in the claims here- 25 to appended; it being understood that various changes in the form, proportion, size and minor details of construction, within the scope of the claims, may be resorted to without departing from the spirit or sacrificing any of the advantages of the invention.

30 In the drawing:—Figure 1 is a plan view of a safety net, constructed in accordance with this invention and shown arranged at the bottom of an elevator shaft. Fig. 2 is a vertical sectional view on the line $x-x$ of Fig. 1.

35 Like numerals of reference designate corresponding parts in all the figures of the drawing.

1 designates a horizontal net, constructed of wire netting, or other suitable material, 40 and arranged at the bottom of an elevator shaft 2, and supported above and in spaced relation with the concrete base 3 of the elevator shaft 2 by coiled springs 4 and 5, arranged beneath the marginal edge of the net and at 45 an intermediate point. The net, which may be made with any size mesh and any strength of wire to suit the height of a building and the size of an elevator shaft, is stretched on and attached at the edges to an open mar-

50 ginal frame 6 of rectangular, or other shape to conform to the configuration of the elevator shaft to which the safety net is to be applied. The upper ends 4^a of the springs are secured to the marginal frame by being partially coiled around the sides thereof, but

they may be connected with the frame in any other desired manner.

The marginal frame, which can be made of any suitable material, may be cheaply constructed of tubular metal, and as illustrated 60 in the accompanying drawing, it is composed of sides connected at the corners of the frame by L-shaped couplings 7. The marginal springs, which may be of any desired number, are designed to be varied in size and 65 strength to adapt them to the height of the building and the size of the elevator shaft, which is to be equipped with the safety net, and they are anchored at their lower ends by means of projecting studs 8, consisting of 70 short pieces of tubing, or other suitable material, embedded in the base 3 and projecting upwardly therefrom. The projecting studs 3 extend into the lower ends of the coiled springs 4 and prevent the springs from 75 becoming displaced. The lower ends of the springs may be secured to the studs, if desired.

In the accompanying drawing a single intermediate spring 5 is shown, arranged beneath the center of the net, but it will be readily apparent that any number of intermediate springs may be employed to prevent the central portion of the net from sagging too much under the weight of a person. 80 This central cushioning means will prevent a person from being thrown against the walls of the elevator shaft by the rebound of the safety net. The upper end of the spring 5 is suitably connected to the net, and the lower 85 end, which is seated on the cement base 3, is anchored by a projecting stud 9, similar to those heretofore described.

When the safety net is subjected to the weight of a person falling down the elevator 95 shaft, the marginal springs will cushion the fall and the net will also yield at the center and increase the cushioning action of the device, so that serious injury will not result when a person accidentally falls down an 100 elevator shaft. If desired, a safety net may be applied to the top of the elevator car to prevent injury to persons falling down the shaft when the car is at the bottom thereof.

Having thus fully described my invention, 105 what I claim as new and desire to secure by Letters Patent, is:—

1. A safety device for elevator shafts comprising an open horizontal frame, a horizontal net secured to and carried by the frame, 110

and a plurality of cushioning springs located beneath the frame and beneath the net in spaced relation with the sides of the frame to assist in maintaining the net in the same 5 horizontal plane as the frame, said springs constituting the sole connection of the net to any point of support and located below the plane of the net at all times.

2. A safety device for elevator shafts comprising an open horizontal frame, a horizontal net secured to and carried by the frame, and a plurality of cushioning springs arranged in spaced relation beneath the frame and constituting the sole support of the same 10 and the net, and means for interlocking the lower ends of the springs with the bottom of an elevator shaft, said springs constituting the sole connection between the net to any point of support and located below the plane 15 of the net at all times.

3. The combination with an elevator shaft, of a safety device comprising an open frame conforming to the configuration of the shaft, a net secured to the frame, coiled 20 springs located beneath the frame and the net and forming the sole support of the same, 25

and studs projecting above the bottom of the elevator shaft and fitting in the lower ends of the coiled springs, said springs constituting the sole connection of the net to 30 any point of support and located below the plane of the net at all times.

4. A safety device for elevator shafts comprising a horizontal net, and yieldable means supporting the net and forming the sole connection of the same to any point of support 35 and located below the plane of the net at all times.

5. A safety device for elevator shafts comprising a horizontal net, and yieldable means 40 supporting the net and forming the sole connection of the same to any point of support and located below the plane of the net at all times, said means being yieldable vertically and laterally. 45

In testimony, that I claim the foregoing as my own, I have hereto affixed my signature in the presence of two witnesses.

JOHN S. KERFOOT.
